UNITED STATES PATENT OFFICE.

JOSAPHAT COUTURE, OF HULL, QUEBEC, CANADA.

WATCH-REPAIR BOX.

1,372,604.

Specification of Letters Patent.

Patented Mar. 22, 1921.

Application filed August 9, 1920. Serial No. 402,497.

To all whom it may concern:

Be it known that I, JOSAPHAT COUTURE, a citizen of the Dominion of Canada, residing at Hull, in the county of Hull and 5 Province of Quebec, Canada, have invented certain new and useful Improvements in Watch-Repair Boxes, of which the following is a specification.

This invention relates to a new system 10 of filing, checking and keeping a permanent record of repairs on watches, jewelry and the like. The objects of the invention are to facilitate the inspection of a watch and record the exact repairs that have to be 15 made, and the costs arising therefrom, and to store the movement of the watch separate from the case, or to store the defective part of the watch or jewelry from the remainder, to keep an exact record of the name and address of the owner, the number of the case, 20 the number of the movement, and all other data which applies to the watch or piece of jewelry then being examined, to provide a checking system whereby the owner of the 25 watch or other jewelry and the watchmaker will have counterfoils corresponding to a stub, which is permanently attached to an envelop or record which forms an original and exact record of the work that has been 30 performed on the said watch.

It is also the object of this invention to have this original record filed after the work has been completed, and during the period in which the work is being performed, this 35 record forms the tracer by means of which the watchmaker can at a moment's notice identify and locate a particular piece of work.

To thoroughly explain the nature of my 40 invention, I have illustrated an embodiment thereof which will now be explained, after which the novelty will be particularly pointed out in the appended claims.

In the drawings, Figure 1 is a perspective 45 view of a container or box, adapted to be used with my improved system.

Fig. 2 is a perspective view of the lid or cover of the box, one end of which is cut away.

50 Fig. 3 is a perspective view of the container or box when closed.

Fig. 4 is a plan view of the front of an envelop which is adapted to be used with the said box in carrying out my system.

55 Fig. 5 is a plan view of the back of the envelop.

Similar symbols indicate corresponding parts in the drawings.

In carrying out my invention, I provide a box or container 1, which may be of any suitable shape but preferably rectangular, having a central wall or division 2, thereby forming the box into two compartments 3 and 4. A lid or cover 5 is provided for the box and one of the ends 6 is cut away, while 60 the side walls of the cover have arcuate recesses 7, which permit of a finger and thumb grip being obtained on the box 1 when removing the lid or cover.

I use with this box, an envelop 8 on the 70 front of which a name line 9 of the owner of the watch is provided, the street address 10, city 11, phone number 12. I also provide information as to whether the completed work is to be mailed, delivered or called for 75 as indicated at 13.

Below this, further provision is also made at 14 for the number of the movement and the number of the case of the watch.

The different sizes are indicated at 15, and 80 at 16 an indication as to whether the watch is of a gold, silver or nickel case, while toward the bottom of the envelop as indicated at 17, a space is left to denote if the watch is of the bracelet type.

85 The flap 18 of the envelop, is formed with transversely extending perforations 19 and 20, allowing two portions to be detached from the flap, and the three portions of the flap and the body of the envelop have a 90 serial number.

The endmost portion of the flap will have printed thereon an indication that it is a receipt of the watch delivered to the jeweler for repairs, and the second portion of the 95 flap will be used as a watchmaker's check, and have the price of the repairs indicated thereon.

On the back 21 of the envelop two vertical columns 22 are provided in which the 100 price of the repairs to be done may be inserted, and at the opposite side of the back, an indication of the several parts of the watch that has been examined, and the noting of the defective parts are inserted.

105 It is preferable that this column will consist of a word "examine" followed by the word "repair," "sell new watch," and then followed by an itemized list of the several parts of the watch, the column being completed by the words "sell movement."

An indication of the number of jewels of the watch will be provided at the foot of the last said column.

On the permanent or undetached portion 5 of the flap, an orifice 23 is provided, which will register when the flap is closed with an orifice 24 in the envelop.

My improved system of filing, checking and keeping a record of the work is as follows: When a customer desires to have a 10 watch examined, the watchmaker takes an envelop 8, and box 1. The end portion 20 of the flap 18 of the envelop is removed and handed to the customer as a receipt or 15 check for the watch left by him.

The second detachable portion of the flap forms the watchmaker's check. When the watch has been disassembled for examination purposes, the defective parts of the 20 watch will be placed in one compartment of the box, say for instance the compartment 4. The watch case and remainder of the watch which is intact will then be placed in the compartment 3.

25 The watchmaker now enters on the back of the envelop the nature of the repairs which would require to be made to put the watch in good condition for use, and in the vertical column 22 he notes the price.

30 On receiving the work to be done, the watchmaker will have entered on the front of the envelop the name of the owner of the watch, his address, etc., shown on the front of the envelop.

35 If the customer wishes to call and find out what repairs will be necessary before instructing the watchmaker to proceed, the watchmaker places the envelop on the top of the box 1, with the flap hanging down 40 over the end of the box. The lid 5 is now placed on the box, and the flap of the envelop with the serial number thereon is visible at the cut away end of the lid. The box may now be placed in any suitable cabinet, and when the owner calls, the watchmaker will be able to locate the box containing the customer's property without any 45 loss of time.

The customer will then be able to view the 50 work which is necessary to be done, and know the exact cost thereof.

The box and envelop constitute a filing system during the repairing of the watch.

When the repairs have been effected the watch is removed from the box and placed 55 in the envelop, and the box is available for use with other watches and with a different envelop. The envelop with the watch therein may be placed in a rack until called for, or until such time as the watch has to be 60 sent away.

The envelop will then constitute a complete and permanent record of the work, and when the flap is folded, the orifices 23 and 24 may be passed over a spear or like 65 file and kept for future reference.

Such files may be alphabetically arranged for the purpose of locating the record at any time in the event of the customer calling at some subsequent period to have other 70 repairs made to his watch.

What I claim as my invention is:

1. A watch repair outfit comprising a receptacle with a cover having a cut-away portion at one end, and an envelop provided 75 with a plurality of flaps some of which are detachably connected and one of which is visible through the cut-away portion of the receptacle, the body of the envelop being concealed within the receptacle. 80

2. A watch repair outfit comprising a receptacle with a cover having a cut-away portion at one end, and an envelop provided with a plurality of flaps some of which are detachably connected and one of which is 85 visible through the cut-away portion of the receptacle, the body of the envelop being concealed within the receptacle, said receptacle being provided with compartments and the receptacle and the envelop constituting 90 a filing system.

3. In a device of the character stated, an identification envelop having place for the address, and other data, and an orifice, said envelop having a flap with transversely extended perforations, to allow a plurality of portions to be detached, and the permanent portion of the flap having an orifice registering with the orifice of the envelop when the flap is closed. 95

In testimony whereof I affix my signature in the presence of two witnesses.

JOSAPHAT COUTURE.

Witnesses:

M. Mc MILLAN,
K. RADY.
